UNITED STATES PATENT OFFICE.

FRANK S. ALIANO, OF NEW YORK, N. Y.

TRUNK-LOCK.

1,083,720.

Specification of Letters Patent.

Patented Jan. 6, 1914.

Application filed May 20, 1913. Serial No. 768,724.

To all whom it may concern:

Be it known that I, FRANK S. ALIANO, a citizen of the United States, residing in the borough of Brooklyn, in the city of New

5 York, county of Kings, and State of New York, have invented certain new and useful Improvements in Trunk-Locks, of which the following is a specification, reference being had therein to the accompanying drawings,

10 which form a part thereof.

My invention relates to trunk locks, and more particularly to a type of swinging hasp trunk lock.

The main object of the invention is to provide a trunk lock having all of the safety factors of the ordinary tumbler lock, in which the safety element will consist of a rotary plate by means of which the bolt mechanism is actuated, said plate being 15 capable of such structural variances as to permit a variance in the wards of different keys, thus securing the same effects as are common in tumbler locks having different "combinations".

25 A further object is to provide a lock of this character, wherein the rotary guard plate will be normally locked against rotation, and when actuated to a certain extent, or by a key having a ward of predetermined 30 length, will be released, but if actuated to a greater or less extent will remain inoperative.

A still further object is to provide a lock wherein the guard plate, by means of a key, 35 may be reciprocated to bring it to a position where it may be rotated, and be capable of subsequent rotation to effect the actuation of the bolt mechanism.

A still further object is to adapt my invention to a "snap" or self-closing lock, or one in which the bolts are normally projected beyond the cup, and are capable of reciprocation independently of, as well as under, the controlling mechanism therefor.

45 A still further object is to provide a lock, the design of which will be simple, the parts few in number and so arranged as to afford the desired factor of safety when the lock is in use, and in which said parts may be conveniently assembled and will not be readily disarranged or subject to such wear as to render the lock inoperative through repeated use. And a still further object is to provide a "snap" lock in which the cup and 50 the parts contained therein will be so compact as to permit the use of the lock with a

keeper plate secured to the outside of a trunk or other receptacle without the necessity for boring the body of said receptacle to accommodate the lower portion of the cup. 60

The invention consists primarily in a trunk lock embodying therein a hasp plate, a hasp pivoted thereto, a cup carried by said hasp, a guard plate, means whereby said plate is permitted to have a reciprocatory movement whereby it may be released, and a rotary movement, whereby said bolts are actuated, means controlled by said guard plate for actuating said bolts, coöperating means carried by said guard plate and said cup, whereby said guard plate is normally locked in relation to said cup, said guard plate having a way therein adapted to receive the wards of a key for reciprocating said plate, and a shoulder thereon adapted 70 to be engaged by said wards for rotating said plate, and a keeper plate; and in such other novel features of construction and combination of parts as are hereinafter set forth and described, and more particularly pointed out 75 in the claims hereto appended.

Referring to the drawings:—Figure 1 is an elevation of a lock embodying my invention, the hasp plate upon the cup being broken away to show the lock mechanism 85 contained in said cup; Fig. 2 is a section on the line 2—2 of Fig. 1; Fig. 3 is a top view of the cup with the controlling mechanism removed, a portion of the cup being broken away to disclose the construction of cup for 90 coöperating with the guard plate and imparting a safety factor to the lock; Fig. 4 is a side view of the preferred form of rotary plate, guard plate and guard plate spring; and Fig. 5 is a bottom plan view thereof. 95

Like letters refer to like parts throughout the several views.

In the form of the invention shown in the drawings, *a* indicates an ordinary hasp plate; *b*, an ordinary swinging hasp pivoted to said plate; and *c*, the cup secured to said hasp plate and containing the bolt and bolt actuating mechanisms. Slidably mounted within the cup *c* is a plurality of reciprocatory bolts *d d'*, which, in the form of the 100 invention shown, are mounted upon the bottom of said cup, the sides of said cup being pierced to permit the projection of these bolts therethrough. These bolts are preferably latch bolts, as shown, the adaptation 110 of the invention illustrated in the drawings and herein described being of a "snap,"

latch or self-locking lock. The bolts d d' are enlarged within the cup as at d^2 d^3 to form stop shoulders for limiting the extent of projection of these bolts, and rearwardly of these extensions, I provide the laterally reduced angular stems d^4 d^5 , which in the form of the invention shown have the two-fold function of forming a spring seat for the springs e e' , and shoulders adapted to 10 coöperate with the bolt controlling mechanism for reciprocating said bolts by means of a key. The controlling means and the balanced condition secured by the springs e e' will limit the bolts to a substantially 15 lineal movement. The cup c may be, and preferably is, of the same diameter throughout, and rotatably mounted therein and resting upon the bolts d d' is the bolt controlling mechanism and guard mechanism; 20 which has the twofold function of limiting the actuation of the lock to a key having certain characteristics, and by a rotary movement, simultaneously withdrawing said bolts within the cup to permit the raising 25 of the hasp. This bolt controlling and guarding mechanism has two essential characteristics, to wit:—that through coöperating means carried thereby and by the cup c , it is normally held inoperative while being 30 capable of release by a reciprocatory movement under the key; and that after such reciprocatory movement, it is capable of rotation to retract the bolts. In the form of 35 the invention shown in the drawings, this mechanism comprises a rotary plate f having pendant studs f' and f^2 adapted to be seated within the angle of the angular stems d^4 and d^5 , and by engagement with the shoulder formed by the short arm thereof, 40 respectively, reciprocate said bolts, clearance beyond said angular stems being provided, as shown, to permit this reciprocation. Upon the upper surface thereof, this plate f is provided with the studs g g' , upon 45 which is mounted the combined reciprocatory and rotary guard plate h , having elongated slots h' h^2 therein adapted to pass over said studs g g' . Said guard plate carries a stud h^3 , and mounted thereon and upon one 50 of said studs as g is a bowed spring i , exerting a constant tendency to restore said guard plate to normal, or to its locked position. Centrally thereof, the plates f and h are each pierced to accommodate the key barrel j , which is of ordinary construction. If 55 desired, a key stud may be used instead of a key barrel, the lock shown, however, being a flat key lock and not a barrel key lock which requires the key stud.

60 Centrally, and about the pierced central opening thereof, the plate h is provided with an opening forming the way h alined with the key barrel j , and the clearance space h^2 , one wall of which, as h^2 , forms a contact 65 surface adapted to be engaged by the ward

of a key for reciprocating said plate, and the wall h^3 of which forms a shoulder adapted to be engaged by the side of said ward for rotating said plate. The size of this opening may be varied at will to change the 70 position of the contact h^2 , relative to the key barrel, thus varying the throw or the reciprocatory movement of the plate with a key having a ward of fixed length, or necessitating a change in the length of the ward 75 in order to secure uniformity in the throw, or reciprocatory movement of the said plate. The shoulder h^3 projects substantially radially of the key barrel j and the contact 80 surface h^2 extends at substantially right angles to said shoulder, an arrangement which secures the application of sufficient force to the said plate to reciprocate it and subsequently rotate it. Opposite the contact h^2 , is a shoulder h^4 , adapted to be engaged by 85 a key to restore the plate h to normal.

By the construction of the guard plate above referred to, to change the "combination" of the lock, it is merely necessary to substitute for a plate in which the contact 90 surface h^2 is of one radial distance from the axis of the key barrel, a plate in which this surface is of a different radial distance from said axis, thus requiring the use of keys having wards differing in length in the same 95 proportion as the radial distance between the contact surfaces of both plates.

The plate h and cup c are provided with coöperating means by which said plate is normally locked in relation to said cup. 100 This means comprises a bolt socket c' in the easing c , and a short bolt h^4 carried by, or formed integrally with, the plate h , and adapted to enter said socket, the spring i being always in tension and tending to normally project said bolt outwardly. This bolt is withdrawn from the socket by the reciprocatory movement of the plate h , and before the plate may be rotated to withdraw the bolts d d' , it is necessary that this bolt 105 h^4 shall be completely withdrawn from said socket. To insure against the actuation of said bolt by a key having a ward of a length greater than would just bring said bolt h^4 within the cup c , I provide the cup c with a 110 bolt opening c^2 , preferably diametrically opposite to the socket c' , and also provide the plate h with a second bolt h^5 adapted to co-operate with said socket, this bolt being normally spaced away from the cup c for a distance equaling the proper quantity of movement of the plate h to withdraw the bolt h^4 from its socket c' . If the movement of the 115 plate under a key be insufficient to fully retract the bolt h^4 , the plate h will remain 120 locked, while if the reciprocatory movement of the plate be more than enough to bring said bolt just within the cup c , or in other words, if the ward of the key be too long, the bolt h^5 will be thrown into the socket c^2 , 125 130

again holding the plate against movement. Hence, to actuate the lock, it is necessary to have a key, the ward of which is of exactly the right length, and various "combinations" 5 may be secured with a single guard plate by changing the radial position of the shoulder k^3 .

To limit the rotary movement of the plate f , I provide said plate with a peripheral 10 channel f^3 , which channel has seated therein an abutment c^3 , carried by the cup c . The construction heretofore described enables me to use a very shallow cup, so that by drawing the head of the hasp b upwardly, as at b' , a 15 shallow lock may be secured. This shallow lock has the advantage that it may be used in connection with what is known as a surface keeper plate, or one having a central opening therein through which the cup is 20 adapted to project, the portion of the keeper plate about said opening being drawn up so as to allow clearance between the plate and the trunk or chest body sufficient to accommodate the bolts d d' . This keeper plate is 25 shown at m in the accompanying drawings, the drawn up portion thereof being indicated at m' .

The operation of the herein described lock will, in the main, be apparent from the foregoing 30 description, but in order to make the invention more clearly understood, a detailed description of the operation of the bolt controlling and guard mechanism will be given.

35 When the parts are locked, they will be in the position shown in Figs. 1 to 3. When it is desired to release the lock, the key is inserted in the key barrel. As the key is inserted, the wards will engage and enter the portion of the clearance space k' to the left. The key is then turned to the right, Fig. 1, the end of the wards engaging the contact surface k^2 and reciprocating the plate h to an extent to completely withdraw the bolt 40 h^4 from the socket c' . If the wards of the key be of the proper length, this will occur just as the side of the key contacts with the shoulder k^3 , as the arrangement of the surface k^2 is such as to have the maximum 45 movement of the plate defined by the junction between the surface k^2 and the shoulder k^3 . The slots h' and h^2 , studs g g' and way k will permit this reciprocatory movement without placing any limitation thereon. If 50 the wards of the key be too short, the plate h will not be reciprocated sufficiently to cause the bolt h^4 to clear its socket c' ; while if on the contrary the wards of the key be too long, the plate would be reciprocated to an 55 extent to cause the bolt h^5 to enter the socket c^2 , prior to, or substantially with, the engagement of the side of the key with the shoulder k^3 , and thus cause the key to lock the plate h against rotary movement and 60 hold it in this locked position. The move- 65

ment of the plate under the key when releasing the lock is against the tension of the spring i . Assuming that the correct key is used, and the plate h is reciprocated thereby to the proper extent, the key may be further 70 turned, rotating the plate h and with it, through the slots h' h^2 and studs g g' , the plate f . The movement of the plate f will through the studs f' f^2 , withdraw the bolts d d' , and permit the hasp to be raised. The 75 springs e e' will permit the retraction of the bolts d d' to the full extent. Immediately upon the unlocking of the bolt, and raising of the hasp, the key may be turned in the reverse direction, the shoulder k^4 to the left 80 of the clearance space k' being engaged by the key and causing the movement of the key to restore the plate h and with it the plate f , to normal. As soon as the bolt h^4 comes into alinement with the socket c' , the 85 spring i will force said bolt into said socket and again lock the plate h in its normal position. The springs e e' with the movement of the plate f , will again project the bolts d d' outwardly, preparatory to the succeeding 90 operation of the lock. This last described operation is characteristic of an ordinary "snap" lock, and is essential to my invention only when my invention is applied to this type of lock.

95 By the construction herein shown and described, I am enabled to produce a lock which may be so finely adjusted as to possess a high factor of safety, and one in which the compound movement of the guard plate 100 is such as to prevent the manipulation of the lock by any means other than a key having a ward corresponding in exact dimensions to that in connection with which the lock is designed to be used.

I have, in the accompanying drawings shown a bolt controlling mechanism which is satisfactory for a lock of the character shown, but this mechanism may be varied without departing from the spirit and scope 110 of the invention. The essential characteristic of my invention is the guard plate having an alternate reciprocatory and rotary movement, normally locked in relation to the cup, the reciprocatory movement thereof disturbing this normal relation and permitting a subsequent rotary movement for actuating the bolt controlling means.

115 Having described my invention, what I claim as new and desire to have protected 120 by Letters Patent, is:—

1. A trunk lock embodying therein a hasp plate, a hasp pivoted thereto, a cup carried by said hasp, a bolt slidably mounted in said cup, a guard plate adapted to have a 125 reciprocatory movement and a rotary movement, means controlled by said guard plate for actuating said bolt, coöperating means carried by said guard plate and said cup, whereby said guard plate is normally locked 130

in relation to said cup and is adapted to be released through the reciprocatory movement of said plate, said guard plate having a way therein adapted to receive the wards of a key for reciprocating said plate and a shoulder thereon adapted to be engaged by said wards for rotating said plate, and a keeper plate adapted to be engaged by said bolt.

- 10 2. A trunk lock embodying therein a hasp plate, a hasp pivoted thereto, a cup carried by said hasp, a bolt slidably mounted in said cup, a guard plate adapted to have a reciprocatory movement and a rotary movement, means controlled by said guard plate for actuating said bolt, coöperating means carried by said guard plate and said cup, whereby said guard plate is normally locked in relation to said cup and is adapted to be released through the reciprocatory movement of said plate, said guard plate having a way therein adapted to receive the wards of a key for reciprocating said plate, a shoulder thereon adapted to be engaged by said wards for rotating said plate, and supplemental coöperating means carried by said plate and said cup whereby in case of excess reciprocatory movement of said plate, it will be locked against subsequent rotary movement, and a keeper plate adapted to be engaged by said bolt.

3. A trunk lock embodying therein a hasp plate, a hasp pivoted thereto, a cup carried by said hasp, a bolt slidably mounted in
35 said cup, a guard plate adapted to have a reciprocatory movement and a rotary movement, means controlled by said guard plate for actuating said bolt, coöperating means carried by said guard plate and said cup,
40 whereby said guard plate is normally locked in relation to said cup and is adapted to be released through the reciprocatory movement of said plate, said guard plate having a way therein adapted to receive the wards
45 of a key for reciprocating said plate, a shoulder thereon adapted to be engaged by said wards for rotating said plate, and supplemental, coöperating means carried by said plate and said cup whereby in case of ex-
50 cess reciprocatory movement of said plate, it will be locked against subsequent rotary movement, means limiting the rotary movement of said plate, and a keeper plate adapted to be engaged by said bolt.

- 55 4. A trunk lock embodying therein a hasp plate, a hasp pivoted thereto, a cup carried by said hasp, a bolt slidably mounted in said cup, a rotary plate superimposed upon said bolt and having downwardly presented 60 means adapted to actuate said bolt, a guard plate mounted upon said rotary plate, co-operating means carried by said rotary plate and said guard plate whereby said guard plate is adapted to have reciprocatory movement independently of said plate and to im- 65

part a rotary movement to said rotary plate, coöperating means carried by said guard plate and said cup, whereby said guard plate is normally locked in relation to said cup, and is adapted to be released through its reciprocatory movement, said guard plate having a way therein adapted to receive the wards of a key for reciprocating said guard plate, and a shoulder thereon adapted to be engaged by said wards for rotating said guard plate, and a keeper plate adapted to be engaged by said bolt. 70 75

5. A trunk lock embodying therein a hasp plate, a hasp pivoted thereto, a cup carried by said hasp, a bolt slidably mounted in said cup, a rotary plate superimposed upon said bolt and having downwardly presented means adapted to actuate said bolt, a plurality of upwardly projecting studs thereon, a guard plate having elongated slots therein inclosing said studs and mounted upon said rotary plate, whereby said guard plate is adapted to have reciprocatory movement independently of said plate and to impart a rotary movement to said rotary plate, co-operating means carried by said guard plate and said cup whereby said guard plate is normally locked in relation to said cup, and is adapted to be released through its reciprocatory movement, said guard having a way therein adapted to receive the wards of a key for reciprocating said guard plate, and a shoulder thereon adapted to be engaged by said wards for rotating said guard plate, and a keeper plate adapted to be engaged by said bolt. 100

6. A trunk lock embodying therein a hasp plate, a hasp pivoted thereto, a cup carried by said hasp, a bolt slidably mounted in said cup, a guard plate adapted to have a reciprocatory movement and a rotary movement, means controlled by said guard plate for actuating said bolt, said cup having oppositely disposed socket openings, oppositely disposed bolts carried by said guard plate and adapted to enter said openings, whereby said guard plate is normally locked in relation to said cup and is adapted to be released through the reciprocatory movement of said plate, said guard plate having a way therein adapted to receive the wards of a key for reciprocating said plate and a shoulder thereon adapted to be engaged by said wards for rotating said plate, and a keeper plate adapted to be engaged by said bolt. 105 110 115 120

7. A trunk lock embodying therein a hasp plate, a hasp pivoted thereto, a cup carried by said hasp, a bolt slidably mounted in said cup, an inwardly projecting angular stem carried by said bolt, a spring having a normal tendency to project said bolt, a guard plate adapted to have a reciprocatory movement and a rotary movement, means controlled by said guard plate for actuating said bolt, said means being so arranged as to 130 125

coöperate with said stem to retract said bolt, while permitting said bolts to be retracted independently of said means, coöoperating means carried by said guard plate and said 5 cup, whereby said guard plate is normally locked in relation to said cup and is adapted to be released through the reciprocatory movement of said plate, said guard plate having a way therein adapted to receive the 10 wards of a key for reciprocating said plate and a shoulder thereon adapted to be engaged by said wards for rotating said plate, and a keeper plate adapted to be engaged by said bolt.

15 8. A trunk lock embodying therein a hasp plate, a hasp pivoted thereto, a cup carried by said hasp, a plurality of oppositely disposed bolts slidably mounted in said cup, each of said bolts being provided with an 20 enlargement within said cup whereby the extent of projection of said bolt is limited, springs simultaneously acting upon both of said bolts for normally projecting them beyond said cup, an elongated angular stem 25 carried by each of said bolts, a rotary plate having a plurality of downwardly presented openings adapted to engage the angular portion of said stems to simultaneously retract both of said bolts, while permitting said 30 bolts to be retracted independently thereof, a guard plate mounted upon said rotary plate, coöoperating means carried by said

guard plate and said rotary plate, whereby said guard plate is permitted to have reciprocatory movement independently of said 35 rotary plate, and to impart rotary movement to said rotary plate, coöoperating means carried by said guard plate and said cup, whereby said guard plate is normally locked in relation to said cup and is adapted to be 40 released through the reciprocatory movement of said plate, said guard plate having a way therein adapted to receive the wards of a key for reciprocating said plate and a shoulder thereon adapted to be engaged by 45 said wards for rotating said plate, and a keeper plate adapted to be engaged by said bolt.

9. In a trunk lock, a lock cup, a key controlled guard within said cup comprising a 50 rotary plate capable of reciprocatory movement, said plate having oppositely disposed bolts adapted to enter sockets in the lock cup, and an opening therein adapted to receive the key and define the extent of reciprocation of said plate thereunder.

In witness whereof, I have hereunto affixed my signature, in the presence of two subscribing witnesses, this 9th day of May, 1913.

FRANK S. ALIANO.
